J. TIMMEL

SELF IGNITING MATCH CONTAINER

Filed May 3, 1922

INVENTOR
Jenny Timmel
BY
F. L. Kekem
ATTORNEY

UNITED STATES PATENT OFFICE.

JENNY TIMMEL, OF RIDGEFIELD, NEW JERSEY.

SELF-IGNITING-MATCH CONTAINER.

Application filed May 3, 1922. Serial No. 558,141.

To all whom it may concern:

Be it known that I, JENNY TIMMEL, a citizen of Germany, residing at Ridgefield, in the county of Bergen and State of New Jersey, have invented certain new and useful Improvements in Self-Igniting-Match Containers, of which the following is a specification.

The main object of this invention is the provision of a pocket match container or safe having means whereby a match is ignited upon withdrawal.

The above and other objects will become apparent in the description below, in which characters of reference refer to like-named parts in the drawings.

Referring briefly to the drawings, Fig. 1 is a perspective view of my container which may be inserted in any common pocket match safe.

Fig. 2 is a vertical cross-sectional view of the safe and my container shown in Fig. 3.

Fig. 3 is a side elevational view of said safe and my container.

Fig. 4 is a cross-sectional view of the same taken on the line 4—4 of Fig. 2.

Referring in detail to the drawings, the numeral 1 represents the hollow back member of my container, the same having a U-shaped lower edge 2 providing a recess or compartment 3 between the edge 2 and back 1. Upon the upper portion of the inner surface of the edge 2 is secured a wedge-shaped tongue extending the width of the edge 2 and having its exposed surface roughened or serrated, as shown.

A vertical slot 5 is provided in the back member 1, said slot communicating with a horizontal slot 5^a. A rod 6 is pivotally mounted at 6^a to the inner side of the hollow back 1, said member being movable in a transverse direction in the slot 5. A horizontal strip 7 is pivotally attached to the lower extremity of the rod 6, and is transversely movable in the slot 5^a. A resilient tongue 8 is secured within the hollow back 1 and urges the rod 6 outward.

The device as thus far described may be placed within any ordinary pocket match safe 9 having the usual cover 10. When the container is to be filled with matches, the same is removed from the safe 9, the member

7 is forced back into the slot 5^a against the force of the tongue 8, and the matches are stacked between the back 1 and edge 2 in the compartment 3. Then the member 7 is released, whence the same will be urged against the matches so that, when a match is withdrawn, its head will engage the roughened surface of the tongue 4, so that the match will be ignited.

If desired, the container 1—2 may be used as a match safe per se by providing walls which will enclose the two ends of the compartment 3.

Thus it is apparent that I have provided a simple and practical match container and safe from which a match may be withdrawn in ignited condition so that the usual striking of the match is eliminated.

I claim:

1. A device of the class described comprising a hollow back member having its lower edge bent into substantially the form of a U in cross-section, so as to provide a match-holding compartment, said compartment being insertable into a match safe, a substantially wedge-shaped tongue having an exposed, roughened edge, said tongue being secured to said lower edge of the back member, and resilient means in the hollow back for normally urging said matches against said roughened edge.

2. A device of the class described comprising a hollow back member having its lower edge bent into substantially the form of a U in cross-section, so as to provide a match holding compartment, a substantially wedge-shaped tongue having an exposed, roughened edge, said tongue being secured to said lower edge, and resilient means for normally urging said matches against said roughened edge comprising a substantially T-shaped slot in said back member, a rod pivotally mounted within said back member and transversely movable in the stem portion of said T-slot, a member rigid with said rod and transversely movable in the arm portion of said T-slot, said member lying in engagement with the matches, and a resilient tongue urging said member against said matches.

In witness whereof I affix my signature.

JENNY TIMMEL,
